(57) **CLAIM**

The ornamental design for a roof truss securement buckle as shown and described.

DESCRIPTION

FIG. 1 is a perspective view of a roof truss securement buckle showing my new design;

FIG. 2 is a top view thereof;

FIG. 3 is a front view thereof;

FIG. 4 is a bottom view thereof;

FIG. 5 is a rear view thereof; and

FIG. 6 is a left side view thereof, the right side view being a mirror image.

FIG. 7 is a left side view thereof in a condition of use;

FIG. 8 is a top view thereof in a condition of use;

FIG. 9 is a perspective view of a second embodiment of a roof truss securement buckle;

FIG. 10 is a front view thereof;

FIG. 11 is a top view thereof;

FIG. 12 is a bottom view thereof;

FIG. 13 is a rear view thereof;

FIG. 14 is a left side view thereof;

FIG. 15 is a left side view thereof in a condition of use;

FIG. 16 is a top view thereof in a condition of use;

FIG. 17 is a perspective view of a third embodiment of a roof truss securement buckle;

FIG. 18 is a front view thereof;

FIG. 19 is a top view thereof;

FIG. 20 is a bottom view thereof;

FIG. 21 is a rear view thereof;

FIG. 22 is a left side view thereof;

FIG. 23 is a left side view thereof in a condition of use; and,

FIG. 24 is a top view thereof in a condition of use.

Right side views not shown are mirror images of left side views.
